[57] CLAIM

The ornamental design for a telephone stand, substantially as shown and described.

DESCRIPTION

FIG. 1 is a perspective view of our new design for a telephone stand, the stand in this embodiment being adapted for use on a horizontal surface;

FIG. 2 is a side elevation view of the telephone stand shown in FIG. 1, the opposite side being essentially a mirror image thereof;

FIG. 3 is a bottom plan view of the telephone stand shown in FIG. 1;

FIG. 4 is a front elevation view of the telephone stand shown in FIG. 1;

FIG. 5 is a rear elevation view of the telephone stand shown in FIG. 1;

FIG. 6 is a top plan view of the telephone stand shown in FIG. 1;

FIG. 7 is a perspective view of a second embodiment of our new design for a telephone stand, the stand in this embodiment being adapted for use on a vertical surface;

FIG. 8 is a side elevation view of the telephone stand shown in FIG. 7, the opposite side being essentially a mirror image thereof;

FIG. 9 is a front plan view of the telephone stand shown in FIG. 7;

FIG. 10 is a rear plan view of the telephone stand shown in FIG. 7; and

FIG. 11 is a top elevation view of the telephone stand shown in FIG. 7, the bottom elevation view being essentially the same as shown in FIG. 5.
